(57) **CLAIM**

The ornamental design for a light fixture, substantially as shown and described.

DESCRIPTION

FIG. 1 is a perspective view of a light fixture embodying the design of the present invention.

FIG. 2 is a front side elevational view of the light fixture illustrated in FIG. 1 on an enlarged scale, with the back side elevational view, right side elevational view and left side elevational view being identical thereto.

FIG. 3 is a top view of the light fixture shown in FIG. 1 on an enlarged scale; and,

FIG. 4 is a bottom view of the light fixture of FIG. 1 on an enlarged scale.
